F. M. SPAYD

LATH

Filed Jan. 9, 1924

Inventor

Fred M. Spayd

By *A. B. Wilcox & Co.*
Attorneys

UNITED STATES PATENT OFFICE.

FRED M. SPAYD, OF VAN WERT, OHIO.

LATH.

Application filed January 9, 1924. Serial No. 685,224.

To all whom it may concern:

Be it known that I, FRED M. SPAYD, a citizen of the United States, residing at Van Wert, in the county of Van Wert and State 5 of Ohio, have invented certain new and useful Improvements in Laths; and I do declare the following to be a full, clear, and exact description of the invention, such as will enable others skilled in the art to which 10 it appertains to make and use the same.

My invention relates to laths for internal or external use in applying plaster, stucco, or the like, and the object is to improve upon the construction of ordinary wooden laths 15 to such an extent as to provide for more effective keying of the plastic material between the laths which are laid in the usual spaced relation.

With the foregoing in view, the invention 20 resides in the novel subject matter herein-after described and claimed, the description being supplemented by the accompanying drawing.

Figure 1 is an elevation of a partly completed wall embodying the improved laths.

Figure 2 is a horizontal section on line 2-2 of Fig. 1.

Figures 3 and 4 are vertical sections on lines 3-3 and 4-4 of Fig. 1.

Figure 5 is a perspective view of one of the laths.

In the drawing above briefly described, I have shown a plurality of the improved laths secured to studs S in the usual way, each lath being indicated by the numeral 1. Each lath 1 is in the form of a flat wooden strip of the same proportions as an ordinary lath, but opposite edges of said lath 1 are formed with spaced elongated notches 2 which are rather shallow. The end walls of each notch are parallel with each other but extend obliquely of the lath, said end walls being indicated by the numerals 3. The end walls 3 at one edge of the lath are in planes at an angle to the end walls at the other edge of said lath and hence it is insured that adjacent edges of any two laths, shall not have their walls 3 running in the same direction. By obliquely positioning these walls 3, acute angular corners

4 are provided at opposite ends of each notch 2, one of these corners being disposed at one side of the lath while the other corner is at the opposite side, and regardless of the way in which the lath is applied, one of these corners at each notch, is operable to form an effective lock behind which the plaster or the like keys.

The laths are applied in the usual spaced relation and consequently, the plaster P will 60 form the usual keys K between adjacent laths, but due to the notches 2, these keys will be formed with extensions E received in said notches. These extensions lock behind the foremost corners 4 of the adjacent 65 laths and thus are effectively keyed in place.

Preferably, in the manufacture of the lath, I drive two lath nails or nails of other suitable size into one of its edges, as indicated by the numeral 5, the headed ends of 70 said nails being allowed to project the proper distance for accurately spacing the laths when they are applied. Thus, a wall 75 may be lathed with much more speed and accuracy than is now possible with the ordinary wooden laths. In fact, the use of these spacers compels the workman to so apply the laths that a sufficient key is formed to insure a permanent job. While I preferably use nails for forming the spacer, any 80 other suitable spacing means may be applied to the laths to accomplish the desired results.

While I have shown and described the invention as embodied in an ordinary wooden 85 lath, it will be understood that the invention may be applied to any size wooden strips and hence the term lath is not used in its limited commercial meaning.

As excellent results are obtainable from the 90 details disclosed, they are preferably followed, but within the scope of the invention as claimed, minor changes may be made.

I claim:

1. A lath comprising an elongated flat 95 strip of wood having shallow elongated notches in its opposite edges, the end walls of each notch being substantially parallel with each other but oblique to the length of the lath, the end walls of the notches at 100

one edge of the lath being disposed in planes at an angle to the end walls of the notches at the other edge of said lath.

2. A lath comprising an elongated flat strip of wood having spaced notches each of which opens through an edge of and through at least one flat side of the strip, each notch being provided with opposed end

walls each of which is disposed at an acute angle to an external surface of the lath, whereby to form locks for the keys formed by the plastic applied to the lath. 10

In testimony whereof I have hereunto affixed my signature.

FRED M. SPAYD.
